UNITED STATES PATENT OFFICE

CHARLES S. CHRISMAN, OF WEST CHESTER, PENNSYLVANIA, ASSIGNOR TO THE U. G. I. CONTRACTING COMPANY, OF PHILADELPHIA, PENNSYLVANIA, A CORPORATION OF DELAWARE

APPARATUS FOR MAKING CARBURETED WATER GAS

Application filed December 10, 1926. Serial No. 153,753.

The sensible heat in the air blast gases is down water gas runs go through the carbureter and which embodies features of the invention, and

5 blue water gas is satisfactorily recuperated in the ash at the base of the fuel bed, and it is one object of the present invention to provide for satisfactorily recovering the heat in the carbureted water gas, thus completing the practical recuperation of the sensible

10 heat in all the gases.

Other objects of the invention are to provide for discharging only coal gases from the set, to reduce the burden on the condensing apparatus, to cool the gas before passing to the valve at the wash box, and to save generator fuel.

Other objects of the invention will appear from the following description but, generally stated, the invention consists in the provision of apparatus for receiving, storing and subsequently giving up heat and hereinafter referred to as a regenerator filled with suitable heat absorbing material and placed at the gas outlet of the superheater of a carbureted water gas set in such a way that carbureted water gas issuing from the superheater passes through it, storing the sensible heat, and cooling the carbureted water gas prior to its entrance into the wash box along with the provision of the necessary valves and piping for using the stored heat to preheat air supplied to the set, or to superheat or generate steam for down steaming, or, in short, for heating gas making fluids.

The invention also comprises the improvements to be presently described and finally claimed.

40 In the following description reference will be made to the accompanying drawings forming part hereof and in which

Figure 1 is a side view, partly in section, of a carbureted water gas set in which the down run gas is led directly to the wash box and which embodies features of the invention.

Fig. 2 is a top or plan view of the same. Fig. 3 is a side view of parts of a carbureted water gas set in which both up and

55 Fig. 4 is a side view, partly in section, of parts of a carbureted water gas set showing features of the invention in a regenerator filled with checkerbrick instead of clinker or loose pieces of heat absorptive material as shown in Fig. 1.

60 A water gas set usually includes a water gas generator 1, a carbureter 2, a superheater 3 having a stack valve 33 thereon, a wash box 4, a waste heat boiler 5, a stack 6, an air supply 7 to the generator 1 controlled by valve 77, and a steam supply 8 controlled by valve 88 to the base of the generator. In some cases there is also included a steam supply 9 controlled by valve 99 to the top of the generator 1 and in all cases the vessels referred to are interconnected as will be hereinafter described. There is nothing particularly new about the carbureted water gas set of which parts have been indicated above. Referring to Fig. 1, the fuel bed in the generator 1 is air blasted from the bottom 7, the blast gas passes by 10 to the top of the carbureter 2, from the bottom of the carbureter by 11 to the bottom of the superheater 3, by 12 from the top of the superheater to the top of the boiler 5, and from the bottom of the boiler to the stack 6, and secondary air is introduced at 13 and controlled by valve 113. The boiler conserves the sensible heat of the air blast gases. This 75 operation is called a blow or blast. The operation of making water gas in the generator is called the run, and it is referred to as either an up or a down run. During the down run the stack 6 is closed, steam is admitted at 9, and the water gas generated in the generator 1, after passing through the clinker at the bottom of the fuel bed in the generator and imparting much of its sensible heat thereto, passes by 14 to the wash box 4, from which it goes by the pipe 15 to storage for use. During the up run which is alternated with the down run and with the air blast as good practice 80 may dictate, steam is introduced at 8, water

85 90 95 100

gas generated in the generator passes by 10 to the top of the carbureter in which it is carbureted by oil or the like introduced at 16, controlled by valve 116, and 5 then by 11, through the superheater 3 which it leaves by the carbureted water gas outlet 17 controlled by valve 117. It is at this point or stage that the present invention is applied. 18 is a regenerator 10 filled with suitable heat absorbing material shown as clinker 19 arranged on a shaking grate 20. The carbureted water gas passes through the regenerator 18 and through the heat absorbing material therein to which 15 it imparts much of its sensible heat and deposits some entrained carbon particles, and the comparatively cooled carbureted water gas passes from 18 by 21 to the wash box 4. From the wash box the cool carbureted water 20 gas passes by 15 to the condensing apparatus, not shown, and for storage or use. The clinker in the regenerator 18 presents a large surface for its volume and therefore the regenerator may be comparatively small. 25 The shaking grate 20 is a means for agitating the clinker to prevent it from being clogged. A depth of three or four feet of clinker may reduce the temperature of the hot carbureted water gas to approximately 500° 30 F. The permissible reduction of temperature depends upon the temperature at which tar condenses from the gas. The regenerator besides removing and storing a large part of the sensible heat in the carbureted water 35 gas reduces the burden on the condensing apparatus and also protects the reversing valve 21 from being subjected to excessive heat.

Piping is provided by means of which the 40 heat stored in the regenerator is used for heating gas making fluids and thus returning the heat recovered from the carbureted water gas to the set. Air may be introduced at 22 controlled by valve 122, heated in the 45 regenerator and passed by the connection 23 controlled by valve 123 to the generator inlet 7 and to the secondary air supply 13 during the blast, and steam for the down run may be introduced at 24 controlled by 50 valve 124, superheated in the regenerator, and passed by 23 and 13 to the top of the generator and in that case the steam supply 9 need not be availed of. By introducing water at 25 controlled by valve 125 into the 55 regenerator steam may be generated therein and used in the manner described for the down run.

The construction and mode of operation of the arrangement shown in Fig. 3, which 60 may be regarded as a modification, are as above described except as follows:

Both the up and down run water gas is 65 passed through the carbureter and superheater and thence through the regenerator 18 to the wash box. For this purpose the down

run water gas is passed from the bottom of the generator by 26 controlled by valve 126 to the top of the carbureter.

In this arrangement air for the blast is preheated in its passage through the regenerator in the manner described. 70

The steam and water connections for the run are omitted from the regenerator 18 and the stored heat is returned to the set by preheating the air for the blasting step. 75

In the modification shown in Fig. 4 the construction and mode of operation are as has been above described except that the regenerator 18^a is internally supplied with heat absorptive material in the form of checker brick and for that reason is shown 80 as somewhat larger.

From the foregoing description of the piping and of the mode of operation it is believed that the valves conventionally indicated in the various figures of the drawings will be understood both as to location and manipulation; therefore a detail description will not be given of them, and after all a water gas set and its operation are 85 thoroughly understood and in this description reference has not been made to certain perfectly well understood steps usually designated as purging with steam. 90

The described apparatus is capable of 95 use in connection with gaseous fluids in another part of the set, namely, the boiler. During the air-blast or blow the blast gas entering the boiler 5, Fig. 1, may for purposes of combustion be supplied with air 100 heated in the regenerator. For this purpose air may be introduced at 22, heated in 18, and delivered by 17, to the blast gas, the valves in 23 and 13 being closed.

It will be obvious to those skilled in the 105 art to which the invention relates that modifications may be made in details of construction and arrangement and in matters of mere form without departing from the spirit of the invention which is not limited to such 110 matters or otherwise than the prior art and the appended claims may require.

I claim:

1. A carbureted water gas set including a generator, a carburetor, a superheater and 115 a washbox, and two conduits for gas leading off from the superheater, one conduit intended for blast gases including a waste heat boiler and a stack, and the other intended for carbureted water gas including 120 a regenerator connected between the superheater and the washbox and adapted to store sensible heat of the carbureted water gas with valves, and connections for introducing air through the regenerator on the way to 125 the set.

2. A carbureted water gas set including a generator, a carburetor, a superheater, a washbox, a conduit leading off from the superheater and intended for blast gases, 130

a waste heat boiler in said conduit, a stack in said conduit, means for leading uprun carbureted water gas from said superheater directly to said washbox, a regenerator in 5 said first mentioned means and adapted to store the sensible heat of the carbureted water gas therein, and means for introducing a gas making fluid or fluids to said set through said regenerator.

10 3. A carbureted water gas set, including a water gas generator having air and steam inlets, a carbureter, a superheater, and a wash box; a conduit leading from the superheater to a waste heat steam boiler, a second 15 conduit leading from the superheater directly to a regenerator containing loose refractory material therein, a conduit leading from the regenerator to the wash box, means for passing air blast gas from the super- 20 heater through the waste heat boiler without passing through the regenerator, means for passing carbureted water gas from the superheater through the regenerator without passing through the waste heat boiler, 25 means for passing air through the regenerator for burning any combustible deposits therein and preheating the air, means for passing the preheated air into the set, and a shaking grate adapted to support the loose 30 refractory material in the regenerator.

4. A carbureted water gas set including a generator and a carbureter and a super- 35 heater and a wash-box and a waste heat boiler and a stack for the superheater, and two conduits for gas leading from the superheater, one conduit intended for leading blast gases to the boiler and stack, and the other conduit intended for carbureted water 40 gas and including a regenerator connected between the superheater and the wash-box and adapted to store sensible heat of the carbureted water gas, and valves and connections for introducing air through the regenerator on the way to the set.

45 CHARLES S. CHRISMAN.
